SPLIT SLEEVE BEARING

Kenneth L. Howell, West Palm Beach, Fla.

Application January 7, 1954, Serial No. 402,649

2 Claims. (Cl. 308—27)

My invention relates to shaft hangers and bearings, and more particularly to hangers and bearings for use in connection with the propeller shafts of boats.

Where propeller shafts pass through the bottom of a boat it is usually necessary to support the end of the shaft near the propeller in a hanger bearing secured to the keel or other part of the boat. Thus nearly all motor boats today are provided with struts and bearings to support the after end of the shaft. Since such bearings are supported beneath the surface of the water they cannot readily be lubricated except by the water which enters the bearing.

For many years these bearings have been lined with rope type packing of flax to support the shaft and at the same time prevent rattling or knocking. Such packing, excellent while new, is subject to wear and has to be replaced frequently.

With the constructions heretofore employed this has been difficult as it usually requires the pulling of the shaft and the removal of the packing by the aid of hooks or other tools. This operation entails a considerable expenditure of time and labor.

The primary object of the present invention is to overcome this difficulty by providing a hanger and bearing so constructed as firmly to hold its packing about the propeller shaft, but which can quickly and easily be disassembled without disturbing the propeller-shaft or strut of the hanger. Other objects will be in part obvious and in part pointed out hereafter.

An illustrated embodiment of my invention is shown in the accompanying drawings wherein Figure 1 is a fragmentary side elevation of the stern of a boat having one embodiment of my invention applied thereto. Figure 2 is a similar view showing a shaft and bearing parts in position for renewal of the flax packing. Figure 3 is an enlarged side view of the bearing and hanger with parts broken away to show the flax packing and other details of construction. Figure 4 is a cross-sectional view taken on line 4—4 of Figure 3; and Figure 5 is a cross-sectional view taken on line 5—5 of Figure 3.

Referring to Figure 1 of the drawings, a portion of a motor boat's stern and bottom 2 is indicated as having a rudder 4, a propeller 6 and a propeller shaft 8. The shaft extends rearwardly through the bottom 10 of the boat. For support adjacent the propeller a hanger bearing is provided comprising a strut 12 and a tubular journal sleeve 14 which is divided longitudinally to form a top half 16 integral with or suitably supported by the strut 12, and a separable bottom half 18. Referring to Figs. 2 and 3 it will be seen that the upper part of the strut 12 is formed as a flange 20 for securing the hanger to the boat bottom by means of bolts or screws 22. Surrounding the shaft 8, within the journal sleeve there is provided a suitable flax rope-type packing 24 of a wettable character such as is commonly used in boat bearings where oil lubrication is not practicable. This packing is wound spirally about the shaft within the space 26 surrounding the shaft, the shaft being of appreciably

2

lesser diameter than the interior of the split journal sleeve 14.

The journal sleeve 14 and its packing are held in position about the shaft by providing its two halves 16, 18 at their ends with matching threaded necks 28 adapted to receive gland collars 30 having internal threads 32 to register with and tighten upon the threaded necks of the split bearing when the two halves of the latter are brought into proper position. In order readily to determine the proper position of the halves, one or more dowel pins 34 may be provided. Seated within each gland collar is an annular washer 36 of rubber or other suitable material to keep out dirt and to engage the ends of the spiral length of packing and which, when the gland collars are tightened, hold the packing securely in place. This action is facilitated when the overall length of the packing coil is somewhat greater than the length of the split sleeve. The gland collars 30 may be held in place by set screws 38.

Since water may penetrate freely to the interior space between the shaft and the sleeve it will be understood that no other lubricant is necessary, and that if proper packing is used the shaft will be supported in a manner to prevent rattling or pounding; further, the split bearing makes it a simple matter to change or renew the packing when appreciable wear has taken place.

Instead of having to pull the shaft, as is generally the case with the usual type of unitary closed bearing the use of my invention makes it possible to renew packing by merely turning back the collars 30 sufficiently to permit the bottom half of the sleeve to be removed and the shaft dropped out of the way far enough to permit a new length of packing to be wound around it until the required amount is in place, after which shaft and bottom bearing half are lifted into place, the collars engaged with the threaded necks of the split sleeve, turned to a tight position against the packing washers and the set screws brought to their set positions.

From the foregoing it will be seen that the objects of the invention set forth above are attained in a simple and practical manner; that the construction readily provides for quick change of packing with a minimum expenditure of time and labor and that the whole bearing structure can be economically produced and installed.

While the hanger strut is herein shown with a flange adapted for attachment to the bottom of the boat, it will be understood that the strut and bearing could be designed to permit attachment to the vertical face of the after part of the keel, and one gland collar only, or a pair of gland collars, could be employed according to the design of the associated parts to hold the halves of the split sleeve together. And other variations of form could be made without departing from the scope of the invention.

I claim:

1. A self-lubricating ship propeller-shaft bearing assembly which can be disengaged from the shaft without axial sliding or movement of shaft relative to bearing, said bearing assembly comprising a shaft, a first longitudinally split-in-half tubular member encircling a portion of said shaft, a fixed supporting strut attached to said member, a second split-in-half tubular member mating with the first and enclosing an annular packing space around said shaft, said members being completely separable from each other from around said shaft without axial movement relative to said shaft, at least one common end of said members being engageable by a surrounding cap adapted to hold said members in encircling relation around said shaft, an integral tubular cap axially slidable along said shaft and engaging a common end of said members to hold them in shaft encircling relation, and a strand of self-lubricating packing material wound

in a spiral around said shaft in said packing space and held closely around said shaft in said space by compression of said cap.

2. The combination of elements as in claim 1 in further combination with a pin engaged through said cap to 5 rotatively lock it onto the end of said member.
